UNITED STATES PATENT OFFICE.

JOHN I. HARRIS, OF SABANO, TEXAS.

WINDOW-SASH CONSTRUCTION.

1,133,472.

Specification of Letters Patent. Patented Mar. 30, 1915.

Application filed March 10, 1914. Serial No. 823,680.

To all whom it may concern:

Be it known that I, JOHN I. HARRIS, a citizen of the United States, residing at Sabano, in the county of Eastland and 5 State of Texas, have invented certain new and useful Improvements in Window-Sash Construction, of which the following is a specification.

My invention relates to a new and useful 10 window sash construction, and its object is to provide a window sash construction, in which certain metal parts together with a packing of card-board or other suitable material are substituted for putty as a means 15 for holding a window pane in a sash.

It is a further object of the invention to provide a window sash construction in which an air tight and water proof joint will be established between the window pane 20 and sash, the means for establishing said joint being such that no especial skill or training is required to do the work, and the joint may be established in a much shorter time than is required to produce the old 25 style putty joint.

It is another object of the invention to provide certain metal parts for holding a window pane in its sash together with a suitable packing to be interposed between 30 said metal parts and the glass, the design of said metal parts and packing being such that they may be readily manufactured in large quantities at a very low expense.

A still further object of the invention is 35 to provide a device of the character described that will be strong, durable, efficient and simple and comparatively inexpensive to produce, also one in which the several parts will not be likely to get out of working order.

With the above and other objects in view, the invention has relation to certain novel features of construction and use, an example of which is described in the following specification and illustrated in the accompanying drawing, wherein:

Figure 1 is a fragmentary view showing the corner portion of a window sash in which the glass is held in the sash by my 50 improved construction. Fig. 2 is a vertical sectional view, taken upon the line $a-a$ of Fig. 1. Fig. 3 is a detail perspective view of a metallic fastening member of which a plurality are used in my invention. Fig. 4 55 is a detail cross sectional view of a sash showing one of the members illustrated in

Fig. 3, bent to the first form which it is given after having been mounted in a sash.

Referring now more particularly to the drawing, wherein like reference characters 60 designate similar parts in all the figures, the numeral 1 denotes a sash, and 2 a pane of glass received by said sash and seated against a shoulder 3 of the sash in the usual well known manner. As a substitute for the 65 putty and triangular tacks ordinarily employed to hold glass in a sash, I employ a plurality of members 4, 5 and 6, the member 4 being a strip of card-board or other suitable packing material contiguous with the exterior face of the glass 2 at its edges. The member 5 is an elongated strip of tin or other suitable metal, angular in cross section, the two integral parts comprising said member being respectively contiguous with 70 the packing 4 and with the inner surface of the sash. To hold the member 5 firmly pressed against the packing 4, a plurality of fasteners 6 are employed, each consisting of a pointed metal strip, which before the glass 80 is introduced into the sash is driven into the inner face of the sash adjacent to the shoulder 3, and is bent outwardly at a right angle as is illustrated in Fig. 4, the outwardly bent portion being received in a 85 channel 6^a formed in the sash. After the glass has been introduced into place in the sash, and the parts 4 and 5 have been arranged in their proper relation to the glass,

the outer ends of the members 6 are bent to 90 the form shown in Fig. 2, embracing the adjacent portions of the members 5 and holding the same firmly contiguous with the packing 4 exerting through said packing a pressure upon the correlated edge of the 95 glass such as will produce an air tight and water proof joint between said edge and the sash. To more positively insure an air proof and water proof joint, it is preferred to coat the packing 4 with oil or paint before 100 using it in the manner above described.

The joint embodying the above described novel features will serve to securely hold a pane of glass in a sash as long as the sash lasts, and may be very quickly produced 105 without the use of especial training or tools. It is to be observed that such a joint may be employed for holding pictures or mirrors in their frames as well as in a window sash construction.

The invention is presented as including all such modifications and changes as prop-

erly come within the scope of the following claims:

What I claim is:

1. In a device of the character described, the combination with a window sash and a pane of glass fitted therein, the sash being formed with a shoulder with which the inner face of the glass is contiguous, of an elongated metal strip of angular cross section having one of its integral parts holding the glass against said shoulder, and its other part contiguous with the inner face of the sash, and a plurality of metallic fasteners driven into the inner face of the sash adjacent to said shoulder, bent outwardly through channels in said face, and embracing the adjacent part of the angular strip holding the same in its proper position.
- 10 15 20 25 30 35 40 45 50 55 60 65 70 75 80 85 90 95 100
2. In a device of the character described,

the combination with a window sash and a pane of glass fitted therein, the sash being formed with a shoulder with which the inner face of the glass is contiguous, of an elongated metal strip of angular cross section bearing against said pane and sash, and a plurality of metallic fasteners driven into the inner face of the sash adjacent to said shoulder, bent outwardly and embracing the angular strip holding the same in its proper position.

In testimony whereof I have signed my name to this specification in the presence of two subscribing witnesses.

JOHN I. HARRIS.
